UNITED STATES PATENT OFFICE

HARRY A. SHAW, OF EAST LANSING, MICHIGAN

DESIGN FOR A RADIATOR

Application filed June 15, 1931. Serial No. 40,217. Term of patent 7 years.

To all whom it may concern:

Be it known that I, HARRY A. SHAW, a citizen of the United States, residing at East Lansing, in the county of Ingham and State of Michigan, have invented a new, original, and ornamental Design for Radiators, of which the following is a specification, reference being had to the accompanying drawings, forming a part thereof.

Fig. 1 is a front elevation of my new design.

Fig. 2 is a horizontal sectional view taken on the line 2—2 of Fig. 1, the screen not being indicated.

Fig. 3 is a side elevational view of the radiator shown in Fig. 1.

Fig. 4 is an enlarged vertical sectional view taken through the cross bar, as on the line 4—4 of Fig. 1.

Fig. 5 is an enlarged vertical sectional view taken through the lower part of the radiator shell, as on the line 5—5 of Fig. 1.

Fig. 6 is an enlarged horizontal sectional view taken through one of the vertical bars, as on the line 6—6 of Fig. 1.

Fig. 7 is an enlarged fragmentary vertical sectional view through the side of the radiator shell, as on the line 7—7 of Fig. 3.

Fig. 8 is an enlarged horizontal sectional view taken through the center bar, as on the line 8—8 of Fig. 1.

I claim:

The ornamental design for a radiator, as shown and described.

HARRY A. SHAW.
